UNITED STATES PATENT OFFICE.

LOUIS K. JOHNSON AND ABBOT AUGUSTUS LOW, OF BROOKLYN, NEW YORK, ASSIGNORS TO THE ALDEN TYPE MACHINE COMPANY, OF NEW YORK, N. Y.

TYPE-SETTING APPLIANCE.

SPECIFICATION forming part of Letters Patent No. 576,731, dated February 9, 1897.

Application filed March 8, 1896. Serial No. 581,688. (No model.)

To all whom it may concern:

Be it known that we, LOUIS K. JOHNSON and ABBOT AUGUSTUS LOW, citizens of the United States, residing in the city of Brooklyn, in the county of Kings and State of New York, have invented certain new and useful Improvements in Type-Setting Appliances, of which the following is a specification sufficient to enable others skilled in the art to which the invention appertains to make and use the same.

Our present invention relates to the form of setter-case set forth in our last application, filed January 30, 1896, Serial No. 577,438, in which a series of interchangeable channel-holders fit into or upon a common table or support. In that case the holders were designed for a single prescribed size of type, containing channels which alone could be properly used in connection therewith.

A distinguishing feature of our present invention consists in adapting the holder to receive and adequately support various widths of type-channels, so as to render the case universal in adaptation, a single case or series of channel-holders answering for all the fonts used in ordinary composition.

Another feature of our present invention consists in making the body of the holder in two parts, which may be readily struck up or forged into shape, one piece fitting upon the table or support and being formed with the type and channel platform, and the other piece being adjustable vertically upon the first to gage the number of types to be removed from the channel, and being formed with a guiding-groove for the upper type and with an opening through which the upper type may be grasped, while still in the said guiding-groove, for withdrawal and removal.

By our present construction any holder in a series may be quickly and conveniently removed from or inserted into position on the common table or support without interfering with or disturbing those next adjoining.

In the accompanying drawings, Figure 1 is a front elevation of a series of channel-holders constructed according to our invention; Fig. 2, a top view of the same. Figs. 3, 4, 5, 6, 7, and 8 are isometrical views of the parts of the holder detached and taken from dif-

ferent sides. Fig. 9 is an elevation of the left-hand side of a holder, channel, &c.; Fig. 10, a front elevation thereof, and Fig. 11 an elevation of the right-hand side of the holder. Fig. 12 is a vertical section upon plane of line 12 12, Fig. 9; Fig. 13, a horizontal section upon plane of line 13 13, Fig. 9; Fig. 14, a horizontal section upon plane of line 14 14, Fig. 9. Fig. 15 is a top view showing a channel in place; Fig. 16, a top view without the channel. Fig. 17 is a central vertical section of a holder and adjoining parts, illustrating the construction and operation of the case. Fig. 18 is a view similar to Fig. 12, illustrating the adjustment of the parts to accommodate a wider channel; Fig. 19 a transverse section also illustrating this feature of adjustment; Fig. 20, a section on plane of line 20 20, Fig. 17, showing the action of the guiding-groove. Fig. 21 is a top view of the adjustable type face-piece; Fig. 22, a side view thereof; Fig. 23, a rear view of the lower portion of a channel, showing the pusher-slot.

The bed plate or table A may be of any desired length, according to the number of words or combinations to be provided for in a single case. Its front portion is formed with a series of equidistant sockets or mortises *a a*, coinciding in size and shape with the tenons *b* on the under sides of the holders B. The rear portion of the table A is formed with parallel grooves *a' a'* for the reception and guidance of the pusher-blades P, the latter being confined therein by a common cap C.

Each pusher-blade P is connected by a pitman *q* with an eccentric which is attached to a disk on a rotating shaft and is acted upon intermittently by mechanism like that shown in our last application, hereinbefore referred to, the operation of forwarding the types being substantially the same.

The holder B consists of the standard plate B', formed with the tenon *b* on its under side below the type-platform *b'*, and having the rectangular flange *b²* on its front side projecting transversely across and above the type-platform *b'*.

The adjustable side wall *B²* is secured to the standard plate B' by a thumb-screw C, passing through the vertical slot *b³* in the rectangular flange *b²*, said slot *b³* being of

greater width than the diameter of the screw to admit of the lateral adjustment of the plates B' B² with relation to each other, as hereinafter set forth.

5 The adjustable side wall B² is formed at the rear with the lateral flange b'', which constitutes the rear wall of the holder. The front of the adjustable side wall B² is formed with the flange b²² projecting laterally over 10 the type-floor b' and formed with the female screw-thread b³³ for the reception of the inner end of the thumb-screw C. The front flange b²² of the adjustable side wall B² is formed with an adjustable face-plate D, secured to 15 it by any suitable mechanism that will permit of its adjustment thereon laterally. The means shown in the drawings consists of two set-screws d, and a binding-screw d', countersunk in the front flange b²² and engaging 20 with female screw-threads formed therein for the purpose, the set-screws d carrying the type face-plate D and regulating its position, while the binding-screw d' binds it in the position desired.

25 The face-plate D is rectangular in cross-section, the flange d² constituting the type face-plate and projecting through the vertical slot b⁴⁴ in the adjustable side plate B². By this means a continuous unbroken 30 surface is presented to the face of the type irrespective of the adjustment of the parts. Thus in most of the figures the holder is illustrated as closed or adjusted to the minimum width of type-channel, while in Figs. 18 and 35 19 the parts are shown as adjusted for a wider channel, in either case the flange b² presenting a uniform surface to the face of the type.

Both the type face-plate D and the lower 40 end of the front flange b²² are formed with extensions d³ and b⁵⁵, extending forward over the type-floor and acting as upper guards to the forwarded types. The inner edge of each 45 extension d³ and b⁵⁵ is grooved so as to form a guiding-channel e between them for the upper type in the word or combination, as illustrated in Figs. 1, 10, 17, and 20. It will be seen that this guiding-channel e is increased or reduced in width by the adjustment of the 50 type face-plate upon the adjustable side wall B², so that the adjustment of the holder with relation to the width of the type-channel regulates the width of the channel e to the width of the type to be used.

55 The adjoining edges of the guard extensions b⁵⁵ d³ are recessed or left open for a short distance from their front edges to give access to the upper side of the highest type to facilitate the grasping or removal of the word or 60 combination.

The spine of the channel F is recessed at its lower end, as at F, Fig. 23, to admit the pusher P, since the lower end of the channel rests directly upon the type-floor b'.

65 It will be seen that the lower edge of the rear flange b'' is in the same plane as the under side of the front guard b⁵⁵ d³, so that the ad-

justment of the side wall B² vertically regulates the space above the type-floor at both front and rear to the height of the type to be 70 accommodated.

The height of the slot f in the spine of the channel F is sufficient to accommodate the maximum number of types, and consequently the largest pusher used. For instance, in 75 the drawings the device is shown as adjusted for five types, representing by way of illustration the maximum number to be accommodated in a single word or combination. Where fewer types are to be used, the adjustable side plate B² is lowered to coincide with their combined thickness; that is to say, to limit the space above the type-floor to that required by their combined thickness, and a pusher of correspondingly less height is substituted for the pusher of maximum height 85 shown in the drawings.

It will be seen that our channel-holders are duplicates and interchangeable, fitting into any of the series of sockets formed in the bed 90 plate or shelf, provided with suitable type-forwarding mechanism for each channel when in place. It will also be seen that each channel-holder presents a perfectly flush even surface on either side, the adjusting-screws being countersunk and there being no lateral protuberance, so that any channel-holder may be removed from the series and another substituted without disturbing the rest.

By our construction we are enabled to apply 100 the channel-holder when in a horizontal or inclined position instead of resorting to the old method of lowering the channel and contents into position in a fixed holder, thereby endangering the alignment of the types. The 105 holder, when applied to the end of a type-containing channel, acting as a support for both types and channel, may be safely and conveniently lowered into position upon a common supporting bed or table, where it is held 110 firmly and rigidly against lateral displacement or movement in any direction by its tenon b, which fits snugly any of the mortises in the support formed for this purpose.

Since in our system of assembling the types 115 in word combinations it is desirable that each channel and holder shall be adapted for use in connection with any word of general use, we form our adjustable side wall with both front and rear type-guarding surfaces in the 120 same plane, so that the adjustment of the side piece controls both the front and rear ends of the type, as hereinbefore set forth. We thus not only hold the advanced types 125 snugly in front until removed by hand, but also counteract any tendency of the pusher, which must be of height equal or nearly equal to the height of the word or combination of types, to withdraw the types backward during its retractile movement.

The adjustment of the plates B' and B² with relation to each other to compensate for and to conform to the adjustment of the face-plate D on the side plate B² is effected by 130

means of the screw C, the slot b^3 in the front flange b^2 being of sufficient width, as compared with the diameter of the screw, to admit of this adjustment, the head of the screw 5 c , or rather the washer c' , acting to bind and hold the plate B^2 in the prescribed position.

What we claim as our invention, and desire to secure by Letters Patent, is—

1. The combination of a channel-holder having one side wall adjustable with relation to the other to compensate for variations in the width of the type-containing channel, of a type face-plate adjustable upon one part of the holder for the purpose of presenting a continuous unbroken surface to the face of the type, substantially in the manner described.

2. A type-channel holder substantially such as described, having a forward extension or type-guard formed with a groove on 20 its underside for the reception and guidance of the highest type, substantially in the manner and for the purpose described.

3. A type-channel holder substantially such as described, having a forward extension or type-guard formed with a groove on 25 its under side for the reception and guidance of the highest type, the upper side of said groove being open near the front end of the guide for the purpose of giving access to the type, substantially in the manner and for the purpose described.

4. The combination of the standard side plate B' , and the adjustable side plate B^2 , formed with front and rear type-guards in the

same plane, substantially in the manner and 35 for the purpose described.

5. The combination of the standard plate B' , the adjustable side plate B^2 , and the laterally-adjustable type face-plate D, substantially in the manner and for the purpose de- 40 scribed.

6. The combination of the standard plate B' , the adjustable side plate B^2 , formed with the forward extension b^{35} , and the laterally-adjustable type face-plate D, formed with the 45 forward extension d^3 , substantially in the manner and for the purpose described.

7. The combination of the standard plate B' , the adjustable side plate B^2 formed with the vertical slot b^{44} , and the adjustable type 50 face-plate D, formed with the lateral flange d^2 , substantially in the manner and for the purpose described.

8. The combination of the standard plate B' , formed with the front flange b^2 , having 55 the vertical slot b^3 , the adjustable side plate B^2 , and the adjusting-screw C, engaging with said side plate B^2 , and of less diameter than the width of the slot b^3 , for the purpose of admitting of the lateral adjustment of the 60 plates B' , B^2 , with relation to each other, substantially in the manner and for the purpose described.
